UNITED STATES PATENT OFFICE.

RALPH D. GARDNER, OF BELOIT, WISCONSIN.

GRINDING MACHINE.

Application filed November 26, 1920. Serial No. 426,357.

To all whom it may concern:

Be it known that I, RALPH D. GARDNER, a citizen of the United States, residing at Beloit, in the county of Rock and State of Wisconsin, have invented certain new and useful Improvements in Grinding Machines, of which the following is a specification.

This invention relates in general to grinding machines, and more particularly to that type known as double spindle disc grinders, which are particularly adapted for simultaneously finishing two opposite parallel faces of various articles or parts adapted to be operated upon by a machine of this character.

In this general type of machine, the grinding wheels are mounted in opposed relation upon spindles, each journaled in a carriage, the carriages being movable toward and from each other to move the grinding wheels toward or from the work which is positioned between them upon a suitable support or work rest.

One of the primary objects of my invention is to provide novel and improved means for regulating the extent of approach of the grinding wheels so that the work will be finished accurately, with the finished faces separated one from the other a uniform and predetermined distance, and to so construct this mechanism that it is capable of a very fine regulation and adjustment, thereby insuring accuracy in the finished product.

Another feature of the invention resides in the provision of novel means for limiting separating movement of the grinding wheels so as to insure against excessive separation which might permit pieces of work or other objects to drop between the wheels and the work rest, with disastrous results to the machine.

Another purpose of the invention is to provide a machine in which one of the wheels may be readily disconnected from the mechanism which moves them toward and from each other, thereby enabling the machine to be used with one wheel only when desired, the other wheel, which has been disconnected from the operating mechanism being moved back into inoperative position. The machine thus possesses not only the advantages of a double spindle grinder, but also is capable of use as a single spindle grinder whenever desirable.

A further feature of the invention resides in the work rest upon which the work or ar-

ticles to be finished are supported during the grinding operations, the work rest in my invention being supported at both ends upon adjustable supports so that the rest extends beyond the perimeter of the grinding wheels at each side and affords a solid, substantial support for the work which is capable of adjustment to any desired position.

Other objects and advantageous features of the invention will be readily appreciated as the same becomes better understood by reference to the following description when considered in connection with the accompanying drawings.

Referring to the drawings:

Fig. 1 is a side elevation of a grinding machine embodying my invention;

Fig. 2 is a plan view thereof; and

Fig. 3 is a transverse sectional view, certain parts being shown in elevation, and certain parts being broken away for clarity.

By reference to the drawings, it will be observed that the machine comprises essentially, a frame or base 5 on which the various working parts are carried. The top of the frame is shaped to provide a pair of tables or guideways 6, upon each of which is mounted a carriage 7. These carriages are each provided with suitable bearings in which the spindles 8 carrying the grinding wheels or discs 9 are journaled. The spindles may be driven by power from any suitable source and may be equipped with belt pulleys if desired, but in the present instance, I have shown each spindle as directly connected with an electric motor 11 by which the grinding wheels are driven.

Both the front and back of the frame 5 are provided with a face plate 12 in which is formed an undercut slot 13 adapted to receive the heads of bolts 14 by which a block 15 is adjustably secured to the face plate so as to be capable of adjustment horizontally when desired. Each block has vertically disposed undercut guide ribs 16, between which is disposed a vertically extending standard 17 which is vertically adjustable in the guideway and is locked in adjusted position by set screws 18. Upon the upper ends of the standard 17, there is fixedly mounted a work rest 19, which extends transversely between the grinding wheels 9 and forms a rest or support for the work or articles to be operated upon by the grinding wheels. It will be obvious that this work rest is rigidly but adjustably supported at

each end, thereby providing a rigid and durable construction and also enabling the work to be inserted between the wheels from each side of the machine, should it be desirable to do so. For the purpose of confining the dust and particles resulting from the grinding operation, I prefer to encase the grinding wheels in a casing 21 of sheet metal or other preferred construction, which is 10 equipped at one or both sides if preferred, with an opening 22, through which the work is introduced into position between the wheels. A suction pipe (not shown) may be connected with the lower portion of the hood 15 or casing to carry away the dust and particles produced by the operation of the machine.

The carriages are moved toward and from each other to bring the grinding wheels into 20 operative relation with the work on the work rest, and to withdraw the same therefrom by means of suitable mechanism which will now be described. The tables 6 are provided with central slots or apertures and the left hand carriage 7, viewing Fig. 1, is equipped with a rack 24, which extends downwardly through this slot centrally of the frame. Upon a shaft 25 extending transversely of the frame, there is fixed a pinion 26, which 25 constantly meshes with the rack 24, the pinion being adapted to be rotated in a clockwise direction, viewing Fig. 1, by means of a hand lever 27 fixed to the outer end of the shaft 26 or by a foot pedal 28 connected with the lever 27 by a link 29. It will be obvious that when the pinion is rotated in a clockwise direction, the left hand carriage will be moved toward the work rest 19, and when pressure upon the hand lever or foot pedal is released, the carriage will be returned to normal position by a weight 31 suspended from a cable 32, which is connected at 33 with the carriage and is trained over a pulley 34 at the end of the machine.

40 The other carriage 7 is also adapted to be connected to and operated by the pinion 26, and with this end in view, I have provided a bar 35 pivoted at 36 to the bottom of the right hand carriage, the bar being extended longitudinally of the machine beneath the pinion 26 and provided on its upper surface near its free end with rack teeth 37. This end of the bar rests upon a cam or eccentric 38 carried by a transversely extending shaft 39 which is equipped at its outer end with a handle or lever 41 by which the cam may be actuated. The cam is so arranged that it affords a support for the rack directly beneath the center line of the gear 26. When the 45 lever 41 is positioned as shown in Fig. 1, the cam 38 will elevate the rack 37 into mesh with the pinion 26 so that upon movement of this pinion, the right hand carriage will be moved equally with, but in an opposite direction to the left hand carriage. Actuation of the

pinion 26 serves therefore, to move the carriages toward each other so as to bring the grinding wheels into operative relation with opposite sides of the work carried upon the work rest 19.

70 Should it be desirable to use the machine as a single spindle, instead of a double spindle machine, the handle 41 is swung in a counterclockwise position to lower the cam 38 and thereby permit disengagement of the rack 37 from the pinion 26. The left hand grinding wheel may then be used as a single spindle machine, while the right hand wheel and carriage remain idle.

75 In order to limit the approach of the grinding wheel so as to ensure accuracy of the finished product, I have provided means independent of the mechanism for moving the carriages, whereby the extent of approach of the wheels may be limited and regulated with a fine degree of accuracy. This mechanism comprises two opposed members, one secured to each carriage, which, as the grinding wheels approach each other, are brought into abutting relation, thereby limiting this approaching movement. One of these members consists of a stop bar 42, which extends through a guide 43 attached to the right hand carriage, and a similar guide 44 attached to the left hand carriage. The right hand end of the stop bar abuts against or is connected to a block 40 adjustably secured by a clamping bolt 46, which operates in an undercut slot 45 formed in the 80 outer face of the carriage 7, to clamp the block 40 in adjusted position and thereby hold the stop bar 42 against movement to the right relatively to this right hand carriage. It will be obvious therefore, that when the carriage is moved toward the left upon approaching movement of the grinding wheels, the stop bar 42 will be correspondingly moved to the left.

85 Upon the left hand carriage in a suitable support 47, I have mounted an abutment member 48, which is disposed in alignment with the stop bar 42 so that upon approaching movement of the carriages, the left hand end of the stop bar and the right hand end of the abutment element 48 are brought into abutting relation, which precludes further approaching movement of the carriages. For the purpose of insuring a fine degree of accuracy in adjustment, the abutment element 48 is equipped with a micrometer adjustment 49, and after the position of the stop bar 42 has been roughly fixed by setting the block 40, the approach of the grinding wheels may be finely regulated by manipulation of this micrometer adjustment, which projects or retracts the abutment element 48 until the exact adjustment is secured.

90 It is also desirable that the separating 130

movement of the grinding wheel be limited in order to obviate so great a separation from the work rest 19 that pieces or articles being operated upon may not accidentally drop between the work rest and one of the grinding wheels during the positioning or withdrawal of the work from the rest. With this end in view, the stop bar 42 is provided at its left hand end with a collar 51 fixedly secured thereto and of such size that it cannot be withdrawn through the guide 44. An adjustable collar 52 is also secured upon the stop bar at the right hand end of the guide 43, and by setting this collar 52 in any desired position, the extent of separation of the grinding wheels may be limited within a reasonable degree. When the separating movement of the carriages takes place, the collar 51, after a limited amount of movement, will be brought into engagement with the guide 44, and the collar 52 being similarly engaged with the guide 43, further separating movement of the carriages is precluded.

It will be apparent, therefore, that I have provided a machine in which the separating movements of the grinding wheels is limited, and capable of adjustment or regulation, and that the approaching movement is also limited, and may be regulated to a fine degree of accuracy by the micrometer adjustment provided. The regulating mechanisms are simple, substantial and durable, the work support or rest affords a support for the work which extends entirely across the faces of the grinding wheels, and the support is capable of adjustment both horizontally and vertically to meet the requirements of any particular kind of work. The grinding wheels are moved toward and from each other by mechanism which is simple in construction and easy to manipulate, and simple means is provided for disconnecting one of the carriages from the operating mechanism so that the machine may be used as a single spindle machine whenever desired.

It is believed that my invention, its construction, mode of operation and many of its inherent advantages will be understood from the foregoing without further description, and it should be manifest that the structural details which have been shown and described as illustrative merely, are capable of wide modification without departing from the essence of the invention as defined in the following claims.

I claim:

1. In a grinding machine, the combination of a pair of opposed grinding wheels, a movable carriage for each wheel, means for moving said wheels toward and from each other, and means including a pair of elements, movable with their respective wheels toward and from the other and adapted to

abut one against the other for limiting the approach of said wheels.

2. In a grinding machine, the combination of a pair of opposed grinding wheels, means for moving said wheels toward and from each other, and a pair of abutment members, each mounted to move with its respective wheel, said members being adapted to limit the approach of said wheels when disposed in abutting relation, and one of said members being adjustable to regulate the extent of approach of said wheels.

3. In a grinding machine, the combination of a pair of grinding wheels, means for moving said wheels toward and from each other, and means including a micrometer adjustment and a pair of members movable upon approaching movement of the wheels into abutting engagement for limiting the approach of said wheels.

4. In a grinding machine, the combination of a pair of grinding wheels, means for moving said wheels toward and from each other, a stop bar connected with one of said wheels to move therewith, and an adjustable abutment member connected with the other wheel to move therewith, said bar and member being movable into abutting engagement upon approaching movement of said wheels to thereby limit such approach.

5. In a grinding machine, the combination of a pair of slidably mounted carriages, a grinding tool carried by each carriage, a stop bar movable with one of said carriages, an abutment member movable with the other carriage in alignment with said stop bar, and means for adjusting the position of said abutment member whereby to vary the extent of approach of said grinding tools.

6. In a grinding machine, the combination of a pair of carriages, a grinding tool mounted upon each carriage, means for moving said carriages toward and from each other, a stop bar mounted upon one of said carriages, an abutment member mounted on the other carriage, said abutment member and stop bar being adapted to be brought into abutting relation with each other upon approaching movement of said carriages, and a micrometer adjustment for said abutment member whereby the extent of approach of said carriages may be regulated.

7. In a grinding machine, the combination of a pair of movable carriages, a grinding tool mounted upon each carriage, means for moving said carriages toward and from each other, and means mounted upon and movable with the respective carriages into abutting engagement with each other for limiting the approach of said tools.

8. In a grinding machine, the combination of a pair of movable carriages, a grinding wheel mounted upon each carriage, a stop bar adjustably mounted upon one of said carriages and projecting in proximity

to the other carriage, and adjustable means mounted upon said other carriage in position to engage with the end of said stop bar upon approaching movement of the carriages whereby to limit the extent of said approach.

9. In a grinding machine, the combination of a pair of movable carriages, a grinding tool mounted upon each carriage, means 10 for moving said carriages toward and from each other, a stop bar guide mounted on each carriage, a stop bar projecting through said guides, means for adjustably locking said stop bar against movement relatively to one 15 of said carriages, and an abutment member adjustably mounted upon the other carriage in position to engage the end of said stop bar upon approaching movement of said carriages to thereby limit the extent of such 20 approach.

10. In a grinding machine, the combination of a pair of movable carriages, a grinding tool mounted on each carriage, means for moving said carriages toward and from 25 each other, a stop bar guide mounted on each carriage, a stop bar extending through said guides, and means on said stop bar preventing withdrawal of said bar through either 30 of said guides whereby to limit the extent of separation of said carriages.

11. In a grinding machine, the combination of a pair of movable carriages, means for moving said carriages toward and from each other, a stop bar guide on each carriage, a stop bar extending through said 35 guides, means on said stop bar co-operating with said guides for limiting separating movements of said carriages, means for locking said stop bar to one of said carriages, and means mounted on the other carriage including a micrometer adjustment, adapted 40 to cooperate with said stop bar to limit the approach of said carriages.

12. In a grinding machine, the combination of a frame, a pair of opposed grinding wheels mounted thereon, a pair of blocks adjustably mounted on said frame, a standard carried by each block, and a work rest extending between said wheels and supported at its ends by said respective standards.

13. In a grinding machine, the combination of a frame, a pair of carriages slidably mounted thereon, a rack mounted upon one of said carriages, a bar connected with the 55 other carriage and provided with rack teeth opposed to the aforesaid rack, a gear wheel disposed between said bar and rack and meshing with said rack, and means for mov-

ing said bar into or out of engagement with said gear to connect or disconnect one of 60 said carriages with said gear.

14. In a grinding machine, the combination of a frame, a pair of carriages slidably mounted thereon, a rack carried by one of 65 said carriages, a gear mounted on said frame and meshing with said rack, a bar pivoted to the other carriage and provided with rack teeth adapted to mesh with said gear, and means for adjustably supporting the free 70 end of said bar to dispose the rack teeth thereof into or out of engagement with said gear.

15. In a grinding machine, the combination of a frame, a pair of carriages slidably mounted thereon, means for moving said 75 carriages toward and from each other, comprising a gear rotatably mounted on said frame and a rack connected with each of said carriages, and means for moving one of said racks into or out of engagement with said gear to thereby connect one of said carriages with or disconnect the same from said gear at will.

16. In a grinding machine, the combination of a frame, a pair of carriages slidably mounted thereon, a gear rotatably mounted on said frame, a rack mounted on one of 80 said carriages and meshing with said gear, a bar pivoted to the other carriage and provided with rack teeth, and a movable support for the rack tooth end of said bar for moving the same into or out of operative relation with said gear.

17. In a grinding machine, the combination of a pair of movable carriages, means for moving the same toward and from each other, comprising a rotatable gear, a rack meshing therewith and connected to one of the carriages, a bar pivotally connected to the other carriage and provided with rack teeth at its free end, and means including an adjustable connection for moving said bar into operative relation with said gear at will.

18. In a grinding machine, the combination of a frame, a pair of carriages slidably mounted thereon, a gear rotatably mounted on said frame, a pair of racks connected respectively with said carriages and adapted to mesh with said gear whereby movement 110 of one of said carriages is imparted to the other in an opposite direction and means whereby one of said racks may be disconnected from said gear.

RALPH D. GARDNER.
